Fixture for Supporting Removable Fingers of Electroplating Racks

William E. Belke, Chicago, Ill., assignor to Belke Manufacturing Company, Chicago, Ill., a corporation of Illinois

Filed June 19, 1963, Ser. No. 75,425

Term of patent 14 years

(Cl. D54—13)

FIG. 1 is a top view in perspective of a fixture for supporting removable fingers of electroplating racks, showing my new design;

FIG. 2 is a top plan view;

FIG. 3 is a front elevational view, the back being the same;

FIG. 4 is a bottom plan view;

FIG. 5 is an end elevational view, the other end being the same;

FIG. 6 is a bottom view in perspective.

I claim:

The ornamental design for a fixture for supporting removable fingers of electroplating racks, as shown and described.
